(57) **CLAIM**

The ornamental design for a kettle bell, as shown and described.

DESCRIPTION

FIG. 1 is a perspective view of a kettle bell;
FIG. 2 is a second perspective view thereof;
FIG. 3 is a top view thereof;
FIG. 4 is a right view thereof and a mirror image of a left view thereof;
FIG. 5 is a front view thereof;
FIG. 6 is a bottom view thereof; and,
FIG. 7 is a rear view thereof.
The broken lines illustrate portions of the kettle bell which form no part of the claimed design.
